UNITED STATES PATENT OFFICE.

KARL VIKTOR RUDIN, OF STOCKHOLM, SWEDEN.

ZERO-SETTING MECHANISM FOR MACHINES OF THE TRINKS TYPE.

Application filed October 31, 1918. Serial No. 260,550.

(GRANTED UNDER THE PROVISIONS OF THE ACT OF MARCH 3, 1921, 41 STAT. L., 1313.)

To all whom it may concern:

Be it known that I, KARL VIKTOR RUDIN, subject of the King of Sweden, residing at 12 Karduansmakregatan, Stockholm, Sweden, 5 have invented certain new and useful Improvements in Zero-Setting Mechanisms for Machines of the Trinks Type (for which I filed an application in Sweden June 22, 1917, No. 1896/17), of which the following is a 10 specification.

This invention relates to means for zeroizing, after each calculating operation, the curve-discs of calculating machines having setting wheels with a variable number of 15 teeth.

One object of the invention is to provide means independent of the above named means, for locking the curve-discs, when set, so as to prevent them from being thrown out 20 of position during the calculating operation, that is to say, during the rotation of the setting mechanism in one direction or the other.

Another object is to provide a zeroizing 25 mechanism by means of which the curve discs, should not the zeroizing operation be completed, are retained in such manner that another setting of the same and, consequently, another calculating operation is 30 made impossible, until the zeroizing operation is completed.

A further object is to so construct the 35 mechanism that the rotation of the setting mechanism and, consequently, another calculating operation, whose result would be incorrect, are made impossible, if the setting of the curve-discs for another calculating operation be effected or the zeroizing mechanism be actuated prematurely.

10 The invention is applicable to calculating machines having a shaft passing through the setting mechanism of the machine and so connected with the curve-discs that the latter, when set, rotate the shaft in one direction, the shaft being connected with a zeroizing member accessible from the outside of the machine in such a manner that the shaft, when actuated by said member, is rotated in the opposite direction thus returning 15 all the curve-discs to zero-position.

The characterizing main feature of the invention consists in that the said shaft is placed within the periphery of the setting 20 wheels and the curve-discs.

By this the advantage is obtained that 55 no separate space is necessary for the zeroizing mechanism which otherwise is the case, as in the devices of this kind hitherto known.

Two embodiments of construction are by 60 way of example illustrated in the accompanying drawings in which—

Fig. 1 is a side-view of a curve-disc with a setting-wheel constructed according to the invention. Fig. 1^a is a modified form of 65 the device shown in Fig. 1. Fig. 2 shows a disc of the zeroizing mechanism viewed from one side and constructed according to one embodiment. Fig. 3 is a side-view of another disc of the same embodiment. Fig. 70 4 is a side-view of details of the locking mechanism for the curve-discs and the handle. Fig. 5 is a front-view, partly in section, of the device shown in Fig. 4. Fig. 6 is a front-view of the discs shown in Figs. 75 1 to 4, when joined together in position of the shaft of the setting mechanism. Figs. 7 and 8 show side-views of two discs of the zeroizing mechanism according to the second embodiment, and Fig. 9 is a front-view 80 of the total zeroizing mechanism according to said second embodiment.

Referring to Figs. 1 and 6 to 9, the setting mechanism of the machine consists, as 85 usual, of setting wheels 1 with curve-discs 2. The curve-discs are, in well-known manner, provided with setting handles 3 and, besides, with internal teeth 4 (Fig. 1) engaging wheels 5 located on a shaft 6 passing through the setting mechanism of the 90 machine. The setting wheels and the curve-discs are provided with slots 49 and 50 respectively for the shaft 6 effecting the setting of the wheels and the discs. If the 95 machine is provided with a result or indicating mechanism, said shaft 6 may consist of the shaft of said mechanism. The shaft 6 is provided with pins or lugs 7, one for each wheel 5, said wheels 5 being loosely journalled on the shaft 6 in such a manner that the shaft, when setting the curve-discs by means of similar pins or lugs 8 secured 100 to the wheels 5, is carried along during the rotation of the wheels 5. In this manner the shaft 6 is set to a position corresponding 105 to the position of the curve-disc in which the greatest number of teeth project. At the one end the shaft 6 is provided with

a toothed wheel 9 or the like (Fig. 2) gearing with an internally toothed wheel or segment 10 secured to the shaft of the setting wheels. The number of teeth of said wheel 10 is so adjusted as to allow the wheel 9 to make a complete revolution. Placed at the end of the gear or segment 10 is a lug or stop 11 adapted to be actuated by the zeroizing member proper, as described below.

According to the embodiment shown in Figs. 1 to 6 said member consists of a suitable number of, say four, bell crank levers 12 pivotally journalled on a disc 13 which is pivotally journalled on the shaft 14 of the setting discs. Said bell crank levers are journalled on pins 15 and provided with rods 16 extending through slots 18 in the disc 13, the slots being so sized as to allow the rods 16 to move sideways. The rods are provided with angular projections 19 (Fig. 6) capable of engaging the lug 11 of the corresponding toothed wheel 10. The bell crank levers 12 are spring-actuated in such manner that the projections 19 generally pass the lug 11 of the toothed wheel 10. When actuated, the bell crank levers are turned so as to put the projection 19 in the path of the lug 11, thus carrying along the wheels 10 and 9.

Spined to the shaft 14 is a toothed sector 17 (Fig. 3) along the periphery of which the rods 16 of the bell crank levers 12 slide during the rotation. Thus the levers are retained in their turned out position maintaining the engagement with the lug 11. The toothed sector is common to all the bell crank levers engaging them in turn, and the length of its periphery corresponds to a fourth of the circular path of said levers.

When being set, the curve-discs are actuated in a well-known manner by pawls 20 (Figs. 1 and 6) actuated by the spring 21 and the hook-shaped portion 22 of which is in engagement with teeth 23 disposed on the curve-disc. The pawls 20 are pivotally journalled on a shaft 24 passing through the setting mechanism of the machine. The curve-discs are set step by step, while subjected to the yielding engagement with the pawls 20.

Preferably, the curve discs are locked in any way during the calculating operation, that is to say, during the rotation of the setting mechanism in one direction or the other, for the purpose of not being removed from the adjusted position during the calculating operation. This is obtained, according to the present invention, by the internal teeth 23 of the curve discs engaging a shaft or bar 25 passing through the setting mechanism and secured, at the one end, to an arm 26 (Fig. 2) and, at the other end, to one portion of a bell crank lever 27 pivotally journalled on a pin 28 (Fig. 4). The

arm 26 and the lever 27 are pivotally mounted on the frame of the machine or any member extending therefrom. The bar 25 is actuated by the zeroizing member, so as to be brought into such a position in relation to the curve-discs, if the zeroizing operation should not be completed, that the curve-discs are unable to be moved to and retained in another setting position.

For this purpose the bar 25 is in engagement with one arm of a pawl 29 (Fig. 2) pivotally mounted on the shaft 24 which is journalled in the frame, the other arm of the pawl 29 engaging a ratchet wheel 30 pivotally journalled on the shaft 14 and fixed to the disc 13, said ratchet wheel being provided with indentures 31 corresponding in number to the zeroizing members (the bell crank levers 12) and, consequently, in the present case four in number, the pawl 29 being adapted to engage said indentures. In the position shown in Fig. 2 the members assume zero-position. On the setting of the curve-discs the toothed wheel 10 is turned in the direction of the arrow in Fig. 2 through a greater or smaller angle in correspondence with the maximal turning of the curve-discs, the toothed wheel then being locked in said position by means of the device described below. On the zeroizing operation effected after the completion of the calculating operation the toothed wheel 10 is turned in a direction opposite to the arrow in Fig. 2, owing to the engagement of the corresponding bell crank lever 12 with the lug 11, the pawl 29, on account of the ratchet wheel 30 being carried along by the disc 13 during its rotation, moving outwards and sliding on the periphery of the ratchet wheel and then, after the zeroizing operation is completed, catching again into the next indenture 31.

Should not, however, the zeroizing operation be completed, the pawl 29 stopping between two indentures 31, the pawl in such case is turned for a short space to the right in Fig. 2, and owing thereto a rod 32 passing through the setting mechanism of the machine is moved inwards towards the center of the disc. At the one end, said rod is secured to the pawl 29 and at the other end to a link 33 connecting the rod with the shaft 24. The rod 32 is so placed above each of the pawls 20 that the rod, in the above-mentioned position of the pawl 29 and the rod 32, moves the pawls 20 out of engagement with the teeth 23 of the curve-discs 2, and consequently, the curve-discs thereby being disengaged from the shaft, no stepwise setting of said discs is possible.

Fig. 1a shows a modification of the device for setting the curve discs step by step. This device differs from that shown in Fig. 1 only in that the shaft 25, instead of bearing directly against the teeth 23, bears

against the upturned end of the pawl 20. According to Fig. 1 the engagement between the pawls 20 and the bars 25, on the one hand, and the teeth 23, on the other hand, is divided between two points for each curved disc, whereas in Fig. 1^a said engagement is effected in one point only.

To prevent unintentional turning of the toothed wheel 10, for instance during the calculating operation, said wheel is preferably provided with a spring-actuated pawl 34 adapted to engage teeth 35 disposed on the disc 13. Thus the wheel 10 may be turned, during the setting of the curve discs, in the direction indicated by the arrow in Fig. 2, the wheel being prevented from turning unintentionally.

The mechanism for locking the curve discs is besides, so constructed that it depends to a certain extent on the position of the handle. For this purpose the bell crank lever 27 supporting the bar 25 is so arranged in relation to a double-armed lever 36 manageable by means of the handle and pivotally mounted on the pin 37, that the bell crank lever 27 together with the bar may be swung downwards to the left in Fig. 4 in the position of repose of the handle (Fig. 5), thus permitting the bar 25 to yield in relation to the teeth 23 of the curve discs, said swinging movement being prevented in the operative position of the handle.

To this purpose the handle is provided, as usual, with a pin 38 moving in the position of repose of the handle a bar 40 towards the machine, while counteracting a spring 39. The inner end of the bar 40 engaging the lower arm of the lever 36 introduces said arm into a recess 42 between two lugs 41. Consequently, in this position of the handle and the lever 36, the lever 27 is capable of moving freely downwards to the position shown by stippled lines in Fig. 4. The handle assuming operative position, the bar 40 moves, owing to the action of spring 39, to the right in Fig. 5, the lever 36, on account of its sliding movement on one of the lugs 41, turning, on the commencing rotation of the setting mechanism, its lower arm outwards and its upper arm inwards. Owing thereto, the lever 27 being unable to swing downwards, the bar 25 will be forced outwards in engagement with the teeth of the curve discs, thus locking the latter, as will appear from Fig. 4.

From this it follows, on the one hand, that another calculating operation cannot be effected, before the handle is locked in its position of repose, and, on the other hand, that, should not the setting of the curve discs be quite correct in case of one tooth 23, for instance, stopping over against the bar 25 (an incompletely adjusted value), the handle and the setting mechanism cannot be turned on account of the upper arm of the lever 36

being unable to turn inwards completely in this position of the bar 25, the lower arm, therefore, being incapable of being moved by the lugs 41.

In the example of construction illustrated in Figs. 7 to 9 the zeroizing mechanism is somewhat modified. The arrangement of shaft 6 and toothed wheel 9 is similar to that shown in Figs. 1, 2 and 6. In this case, however, said wheel gears with a toothed wheel 43 journalled on the shaft 14 of the setting mechanism and having the same number of teeth as wheel 9. Journalled at the side of said wheel 43 is another wheel 44 engaging a toothed wheel 45 having preferably double the number of teeth of the wheel 44. The wheel 45 is connected with a thumb-screw 46 or the like.

The zeroizing operation is effected in this case by turning the zeroizing member proper (the thumb-screw) through an angle of 180°, whereas the said operation is effected in the embodiment shown in Figs. 1 to 6 by rotating the zeroizing member (the bell crank lever 12) a quarter of a revolution.

In Fig. 7 the different members assume the zero-position. On setting the curve discs for performing a calculating operation the wheel 9 should be able to rotate freely, i. e., to follow the movement of the curve discs. To this purpose one tooth is removed from the wheel 43 (Figs. 7 and 8)—it being observed that the wheels 44 and 45 are supposed to be left out in Fig. 8—and owing thereto the wheel 9 can be rotated by any number of teeth, for instance four, as shown in Fig. 8. After the completion of the calculating operation the zeroizing of the curve discs is to be effected. The thumb-screw 46 is turned through half a revolution in the direction of the arrow, the wheel 44 thereby being turned a revolution in the direction of the arrow. At the same time the wheel 43 is carried along, its teeth turning the wheel 9 back by four teeth and consequently to zero-position. Continued turning of the wheel 43 will be of no influence on the wheel 9 and the curve-discs, because of the wheel 9 also being without one tooth. In case of the curve-discs not being adjusted to any value, the wheel 9, consequently, can be turned independently of wheel 43 and the latter independently of wheel 9.

Though in the drawing the wheels 43 and 44, for the purpose of clearness, are supposed to consist of two separate wheels having different diameters, said wheels may be joined together to form a single wheel having teeth of double the length. In this case one of the teeth is to be half truncated in order to obtain room for the free movement of the wheel 9.

For the purpose of preventing the wheel from being turned too far, for instance in case of rapid setting of the curve discs, an

additional toothed wheel 47 is disposed on the shaft 6 at the side of the wheel 9, said wheel 47 being engaged by a pawl 48. Preferably, said pawl is double armed, one of the arms forming the arm 26 shown in Fig. 2 and supporting the bar 25. The ratchet wheel 30 is connected with the wheel 43 and provided with one indenture 31 only to be engaged by the pawl 29.

10 The operation of the device will appear from the above description and the drawing and will, therefore, be omitted.

Obviously, the device may be modified in many respects without deviating from the 15 principles of the invention.

Claims:

1. In a calculating machine of the Trinks type, setting disks having adjustable teeth and cam disks actuating said teeth, said 20 disks having openings between their centers and peripheries, a shaft on which said disks are mounted, a setting shaft passing through said openings of said disks, a toothed gear on said setting shaft, a toothed element 25 mounted on the first named shaft, and a zeroizing member comprising a disk arranged at one side of said toothed element, adapted to be manually turned from without, and bell crank levers mounted on said disk 30 and arranged for successive engagement with said toothed element.

2. In a calculating machine of the Trinks type, setting disks having adjustable teeth and cam disks actuating said teeth, and also 35 provided with internal teeth, and means for setting the curve disks step-by-step, said means comprising a pawl to engage said internal teeth, and zeroizing mechanism by which said pawl is actuated, and including 40 means to completely release the pawl from the corresponding cam disk in the event of defective zeroizing operation.

3. In a calculating machine of the Trinks type, setting disks having adjustable teeth 45 and cam disks actuating said teeth, and also provided with internal teeth, and means for setting the cam disks step-by-step, said means comprising a pawl to engage said internal teeth, and zeroizing mechanism by 50 which said pawl is actuated, and including means to completely release the pawl from the corresponding cam disk in the event of defective zeroizing operation, said releasing means including an actuating bar passing 55 through the setting mechanism, a link attached to one end of said bar, and a zeroizing-mechanism-actuated element at the other end of said bar.

4. In a calculating machine of the Trinks 60 type, setting disks having adjustable teeth and cam disks actuating said teeth, and also provided with internal teeth, and means for setting the cam disks step-by-step, said

means comprising a pawl to engage said internal teeth and zeroizing mechanism by 65 which said pawl is actuated, and including means to completely release the pawl from the corresponding cam disk in the event of defective zeroizing operation, said releasing means comprising an actuating bar passing 70 through the setting mechanism, a link attached to one end of said bar, a pawl at the other end of said bar, and a ratchet wheel for engagement by said pawl and arranged to rotate with the zeroizing mechanism. 75

5. In a calculating machine of the Trinks type, setting disks having adjustable teeth and cam disks actuating said teeth, and also provided with internal teeth, and means for setting the cam disks step-by-step, said 80 means comprising a pawl to engage said internal teeth, and zeroizing mechanism by which said pawl is actuated, and a bar yieldingly engaging the teeth of each cam disk.

6. In a calculating machine of the Trinks type, setting disks having adjustable teeth and cam disks actuating said teeth, and also provided with internal teeth, and means for setting the cam disk step-by-step, said means comprising a pawl to engage said internal 90 teeth, zeroizing mechanism by which said pawl is actuated, and a bar yieldingly engaging the teeth of each cam disk, an arm secured to one end of said bar, and a bell crank lever having one arm secured to the 95 other end of said bar and the other arm arranged for actuating by the handle of the machine.

7. In a calculating machine of the Trinks type, setting disks having adjustable teeth 100 and cam disks actuating said teeth, and also provided with internal teeth, and means for setting the cam disks step-by-step, said means comprising a pawl to engage said internal teeth, zeroizing mechanism by 105 which said pawl is actuated, a bar yieldingly engaging the teeth of each cam disk, an arm secured to one end of said bar, a bell crank lever, having one arm secured to the other end of said bar, and the other arm arranged 110 for actuation by the handle of the machine, and a double armed lever actuated by the handle of the machine and so arranged with respect to the bell crank lever as to enable the latter to be swung, together with the bar, 115 independently of the double armed lever, only when the handle is in the position of repose, and thus cause the bar to yield in relation to the said internal teeth of the curve disks. 120

In testimony whereof I affix my signature in presence of two witnesses.

KARL VIKTOR RUDIN.
